UNITED STATES PATENT OFFICE.

FRANCIS V. PHILLIPS, OF CHICAGO, ILLINOIS, ASSIGNOR TO THE CHICAGO SASH PULLEY COMPANY, OF SAME PLACE.

SASH-CORD GUIDE.

SPECIFICATION forming part of Letters Patent No. 374,158, dated November 29, 1887.

Application filed April 15, 1887. Serial No. 234,893. (No model.)

To all whom it may concern:

Be it known that I, FRANCIS V. PHILLIPS, of Chicago, in the county of Cook and State of Illinois, have invented certain new and useful Improvements in Sash-Cord Guides; and I do hereby declare that the following is a full, clear, and exact description thereof, reference being had to the accompanying drawings, and to the letters of reference marked thereon, which form a part of this specification.

This invention relates to certain features of construction in the shells of sash-pulleys or sash-cord guides, which have reference to the manner of securing the shells in straight-through mortises in the frame-stiles.

Primarily the invention consists in the provision of a flange for a screw or other fastening on the upper end of the shell, which flange is of no greater width than the cord-groove in the sash, and which, instead of being sunk in the stile, rests thereon and fails to interfere with the movements over it of the sash, because it is embraced or accommodated in the cord-groove in said sash. This novel feature may be employed in conjunction with any suitable fastening or holding means for the lower end of the shell within the broad terms of my claims; but my invention consists, secondarily, in a pulley-shell provided with such a superficial flange at its upper end and with a concave lower end, (viewed in side elevation or section,) whereby the lower end of the shell is depressed into the lower wall of the mortise at the inner surface of the stile, and thus held from displacement when the upper end is fastened.

In the accompanying drawings, Figure 1 is a face view of my improved pulley-shell. Fig. 2 is a central vertical section in the central plane of the pulley. Fig. 3 is a transverse section through x x of Fig. 2. Fig. 4 is a transverse section in the same line (x x of Fig. 2) of a shell not having said guard-flanges.

A represents a pulley-shell cast in a single piece; B, a grooved wheel mounted thereon, over which the sash-cord is trained.

C is a window-stile having a mortise, c , in which the shell A is secured.

As a novel means of securing the upper end of the shell to the stile, the shell is provided with a vertically-projecting flange, A', which

lies upon the outer surface of the stile C, and which has a hole through it for the admission of a screw, D, by which to fasten the flange A' down firmly upon the face of the stile C. In order that the flange A' may thus lie upon or wholly outside the stile, and yet not interfere with the raising of the sash, said flange is made no wider than the cord-groove, whereby it enters the groove as the sash is raised over this part of the shell.

Any suitable fastening device for securing the lower part of the pulley-shell may, manifestly, be employed; but I have herein shown and described an improved construction for this purpose, intended to be used in connection with a straight mortise in the window-stile—meaning by a straight mortise one having its end walls at right angles with the face of the stile. This improved construction consists in providing the shell with a relatively narrow cross-piece, a , at its lower end, less in width than the thickness of the stile and occupying the outer part of the mortise, as shown in Fig.

2. In conjunction with this narrow cross-piece the side walls, a' , of the shell are extended longitudinally of the shell beyond the cross-piece a , so that they may be forced into the wood at the inner portion of the lower end of the mortise c , as also plainly indicated in said Fig. 2. In conjunction with this construction I prefer to make the upper end of the shell downwardly and inwardly inclined, as shown at a^2 and as heretofore made, so that by first placing the lower end of the shell in the mortise and then forcing in the upper end the shell will be crowded down to depress itself into the wood of the stile C at the projecting points a and a' .

In this construction of the shell the flange A', by meeting and resting upon the surface of the stile C, definitely limits the inward movement of the shell under a blow of the hammer or other pressure, so that the shell is easily and quickly brought to place in the mortise. The narrow flange A' being arranged to rest upon the outer plane surface of the stile C, the trouble and expense of cutting a relish, as heretofore universally done when the shell has had flanges, is saved.

It is very desirable to make the mortise c in the stile C somewhat wider than the shell, in order to avoid splitting of the stile in driving

the pulley-shell to its place therein. When the shell is provided with side flanges, as part of what is known as a "face-plate," this is easily done, as the side flanges cover the spaces thus allowed; but it is the purpose here to avoid cutting a relish at any point, and to utilize the plain mortise as it is here shown. This of course involves the omission of the side flanges from the shell; yet it is desired to provide full or excessive lateral breadth in the mortise, and at the same time to fill the mortise on the outer face of the stile to present a workmanlike appearance. To attain these ends I provide the shell with very narrow and thin ribs or fins, a^3 , on its opposite sides, which give greater breadth to the shell at the very face of the stile than farther inward. These fins fill the little spaces intended to be allowed in the mortise, and yet, in case the mortise shall be filled by the body of a shell which is rather wider than others, they are easily depressed into the wood without either hindering the insertion of the shell or tending to split the stile.

I claim as my invention—

1. A shell of a sash-cord guide, provided with an end flange or projection arranged to bear on the outer plane surface of the window-stile, of suitable width to enter the cord-groove of the sash to permit the sash to be raised over the sash-cord guide, substantially as described. 25

2. A sash-pulley shell having a cross-piece or end piece at its lower end, which extends inward from the front face of the stile, but is of less horizontal depth than the stile, the 35 side walls of the shell at the rear of said lower end piece being extended downwardly beyond the end piece, whereby said side-wall extensions may be forced into the wood at the lower end of the mortise in the stile, substantially 40 as described.

In testimony that I claim the foregoing as my invention I affix my signature in presence of two witnesses.

FRANCIS V. PHILLIPS.
